UNITED STATES PATENT OFFICE.

WALLACE M. HOULDSWORTH, OF ROYAL OAK, MICHIGAN.

LAPPER.

Application filed April 5, 1923. Serial No. 628,971.

To all whom it may concern:

Be it known that I, WALLACE M. HOULDSWORTH, a citizen of the United States, residing at Royal Oak, county of Oakland, State of Michigan, have invented a certain new and useful Improvement in Lappers, and declare the following to be a full, clear, and exact description of the same, such as will enable others skilled in the art to which it pertains to make and use the same, reference being had to the accompanying drawings, which form a part of this specification.

My invention relates to an improved lapping machine. It is illustrated in a specific embodiment intended for use with cylinders or other tubular bodies.

An object is to provide an improved rotary lapper adapted to finish a cylinder or other similar work to a true radius, and which will remove an out-of-round irregularity existing in such body and will not conform in its rotation to such an out-of-round condition and accentuate it, and a meritorious characteristic of my improvement is the use of a lapping element so constructed as to engage the lapped surface at a plurality of circumferentially spaced points, thereby preventing a lapping stone from falling into an out-of-round depression in the lapped surface.

A further object is to provide a rotatable lapper having lapping stones held normally outwards by uniform yielding pressure to engage the work, which stones may be retracted radially to permit withdrawal of the lapper from the work without interrupting the rotation of the work, and an important feature of this improved construction is the provision of mechanism so arranged that the rotation of the lapper may be utilized to retract the lapping stones to permit withdrawal of the lapper from the piece upon which it is working.

In the drawings,—

Figure 1 is a side elevation of my improved lapper.

Fig. 2 is a cross-sectional view taken on the line 2—2, Fig. 1.

Fig. 3 is a bottom plan of the lapper shown in Fig. 1.

Fig. 4 is a sectional view taken on the line 4—4, Fig. 2.

Fig. 5 is a sectional view taken on the line 5—5 of Fig. 2.

My improved lapper comprises a supporting body provided with a suitable shank

adapted to be detachably engaged with a power-driven rotatable spindle to rotate therewith, which body is adapted to carry a plurality of removable lapping stones held yielding outwards to engage a piece of work, which stones are so constructed as to individually engage the work at a plurality of circumferentially spaced apart points through an arc of sufficient extent to prevent any stone from falling into an out-of-round depression in the lapped surface.

I provide a supporting body 10 cored out to provide a plurality of spaces 11, which body is carried by a suitable shank 12 secured to the body by a plate 13. This plate 13 is secured to the end of the shank by a screw 14 and to the body by a plurality of screws 15. The body 10 is provided with a plurality of spiral grooves 16, each of which is adapted to serve as a seat for a spiral lapping stone 17. These stones are held yieldingly outwardly radially by means of a plurality of suitable substantially equally spaced springs 18.

In the construction shown I prefer to provide springs which will exert a slight upward pressure as well as outward pressure on the several lapping stones and also exert a uniform pressure on each of the lapping stones. The springs here shown are flat spring members provided with radial extensions to engage each lapping stone. These springs are disposed in the cut-out portions 11 of the body and may be held in place by means of suitable screws. The uppermost spring 18 is secured in position by a sleeve 22 which is interposed between the plate 13 and a shoulder formed on the shank. The next lowermost spring is held in position by a screw 19 engaging it to the body, as appears in Fig. 2. The lowermost spring 18 is secured in position by a screw 20, which screw also secures a retaining plate 21 to the lower end of the body, a spacer tube 22 encircling the screw between the retainer plate and the spring to hold the spring upwardly within the body.

The lapping stones will have a limited radial movement, as will appear from the drawing, and are held in place by retaining plates at each end. Each lapping stone is beveled at the ends and the retaining plates are so shaped as to engage these beveled ends. The retaining plate 21 which is secured to the lower end of the body by a screw 22 engages the lower end of the lap-

ping stones and an axially movable retaining plate 23 engages the upper extremities of the lapping stones. This retaining plate 23 is held outwardly to engage the lapping stones by a spring 24, one end of which engages the plate and the other end of which is received within a recess 25 formed in a gripping member 26. This gripping member 26 carries pins 27 which extend radially 10 into a spiral groove 28 formed in the shank 12. The normal position of the gripping member is that shown in Fig. 2, the radially extending pins 27 being in the uppermost extremities of the groove, the spring 24 being under compression to hold the retaining plate 23 downwardly against the lapping stones.

After a piece of work has been lapped and it is desired to remove the lapper, this may 20 be done without interrupting the rotation of the lapping tool by gripping with the hand the gripping member 26 so as to arrest its rotation, which will permit the shank to overrun the gripping member and 25 cause the gripping member to move downwardly over the shank as the pins 27 travel downwardly through the groove 28 circumferentially the shank. This downward movement of the gripping member axially 30 the shank forces the retaining plate 23 downwardly and due to the beveled construction of the ends of the lapping stones causes the lapping stones to move inwardly radially the tool against the outward yielding 35 pressure maintained thereon by the springs 18 and permits the withdrawal of the lapping tool from the work. The spiral groove 28 is provided at a point approximate the lowermost extension thereof with 40 a pocket 29, into which the pin 27 may fall when it registers therewith. This will serve to secure the gripping member in the depressed position and retain the lapping stones in the retracted position.

45 What I claim is:

1. In a lapper, in combination, a rotatable body having a plurality of seats for spiral lapping elements, a plurality of spiral lapping elements individually removably receivable within the provided seats of the body, said elements extending lengthwise the body and circumferentially thereof but less than half way around the body, and releasable retaining means engaging the ends 50 of said elements to secure them in their provided seats adapted to permit limited movement radially of the elements during operation.

2. In a lapper, the combination with a rotatable body having a support for a spiral lapping element, a spiral lapping element

having beveled ends disposed within said support and means holding said element yielding outwardly, and beveled retaining plates engaging the beveled ends of the lapping element to hold the same in place adapted to permit radial and axial movement of the element.

3. In a lapper, a rotatable body having a spiral seat for a lapping element, a lapping element having beveled ends disposed within said seat, end plates engaging the beveled ends of said lapping element to hold the same removably in place adapted to permit radial movement of the lapping element relative its seat, one of said end plates held against said lapping element under yielding pressure to yield axially, spring members holding said lapping element yieldably outwardly radially, a gripping member 70 normally rotatable with said support engaging therewith and with the movable end plate to force the plate axially to actuate the lapping element radially upon the arrest of rotation of the gripping member permitting 75 the support to overrun the same.

4. In a lapper, a rotatable tool-holding body having beveled ends and a spiral seat for a lapping element, a lapping element having beveled ends positioned within the spiral seat of the body, end plates carried by the body adapted to engage the beveled ends thereof and the ends of the lapping element to hold the element upon its seat adapted to permit movement of the element 80 radially upon its seat, one of said end plates held yieldably in engagement with the lapping element.

5. In a lapper, a rotatable tool-holding body having a plurality of spiral seats for lapping elements, said body cored out 10 interiorly, spring members disposed therein, each member having a plurality of leaves, one engaging each lapping element to exert 15 pressure thereon radially.

6. In a lapper, a rotatable tool-holding body having a plurality of spiral seats for lapping elements, said body cored out 20 interiorly, spring members disposed therein, each member having a plurality of leaves, one engaging each lapping element to exert 25 pressure thereon radially, said lapping elements having beveled ends, beveled end plates engaging the ends of said lapping elements to hold them upon their provided 30 seats, one of said end plates being stationary, the other end plate held against the lapping elements under yieldable adjustable 35 pressure.

In testimony whereof I sign this specification.

WALLACE M. HOULDSWORTH.
